TITLE

James C. De Vol, Louisville, Ky., assignor to The
Sani-Tile Company, Inc., Louisville, Ky.

Application October 14, 1931. Serial No. 568,697

4 Claims. (Cl. 72—19)

The main object of my invention is to provide an improved tile which is economical to produce, ornamental in appearance, and relatively easy and inexpensive to lay.

5 Another object of the invention is to provide a tile comprising a sheet metal shell having a perforated filler plate of fibrous material, whereby to permit the rapid application thereof to Celotex, Insulite, and similar wall boards with 10 a very small amount of cementitious material or the like.

A further object is to prevent the weakening of the wall board against which the tile is laid.

Objects relating to details and economies of my 15 invention will appear from the description to follow. The invention is defined and pointed out in the claims.

A structure which is a preferred embodiment of my invention is illustrated in the accompanying 20 drawing, in which:

Fig. 1 is a fragmentary view of a wall having my improved tiles laid thereon.

Fig. 2 is an enlarged fragmentary section of this wall.

25 Fig. 3 is a perspective view of one of the elements of the tile.

Referring to the drawing, numeral 1 indicates a wall, floor, or the like, consisting of wall board, such as Celotex, Insulite, or the like, and 2 the 30 cement by means of which the shell-like tiles 3 are secured together. The tile 3 comprises shell-like sheet metal face plates 4 and filler plates or strips 5 of fibrous material, such as asbestos, mill board, or some of the cheaper fibrous boards 35 or the like which are comparatively light in weight and effective as insulators and also of sufficient body so that they serve as stiffening and supporting members for the wall board and filler and bonding plates for the sheet metal tile.

40 The face plates of the tile have rearwardly extending flanges 7 of a width substantially exceeding that of the insulating plates so that when the plates are arranged within the flanges there is a substantial space left for the cement 2. The

45 filler plates are preferably secured directly to the wall board 2 by means of nails or the like and are provided with holes 6 therein arranged in spaced relation, the holes being shown in the drawing somewhat out of proportion for convenience in illustration. The holes 6 provide for

50 the direct bonding of the cement therewith. The filler plates almost entirely fill the space within the shell-like tile and thereby reduce the required amount of bonding material or cement to a minimum. The liner strips or filler plates also permit

the very rapid application of the tile to the wall board, and since the wall board is protected from direct contact with the cement, except below holes 6, the structure of the wall board is not weakened thereby.

I am also able to provide tiles of considerable size employing comparatively thin material for the face plates; at the same time these are supported so that they do not buckle or warp, the fibrous material serving both to insulate as to 65 heat and cold and where asbestos is used, as a fire insulation, and also as sound insulation.

In laying the tile, the wall board 1 is first secured to a suitable foundation or frame (not shown). The filler plates 5 are then nailed to the 70 wall board in spaced relation, the space between the tiles being just sufficient for the introduction of the rearwardly extending tile flanges 7. Each tile is then partially filled with cement and applied over a filler plate, in this operation the 75 cement being forced into the perforations 6. Each tile 3 is pressed home until its flanges 7 engage the wall board 1. While I prefer to place the tiles with their flanges in abutting relationship without the use of cement, it will be apparent to 80 those skilled in the art that the tiles may be spaced far enough apart to permit the introduction of cement between them if desired.

My improved tile is very economical to manufacture and can be easily laid, it being especially 85 desirable when embodied in tiles of considerable size for use in public buildings such as schools, gymnasiums and the like, although well adapted for use as wall tiles in a great variety of relations. The face plates may be ornamented by enameling, either vitreous enamel or enamel paint or otherwise coated as may be desired.

It is obvious that various changes and modifications may be made in the details of construction and design of the above specifically described embodiments of my invention without departing from the spirit thereof, such changes and modifications being restricted only by the scope of the 95 following claims.

Having thus described my invention, what I 100 claim as new and desire to secure by Letters Patent, is:

1. A wall comprising a foundation sheet, spaced perforated filler plates secured to said sheet, rearwardly flanged shell-like tiles disposed over said 105 plates with their flanges engaging the foundation sheet, and cement bonding said tiles to said plates, the latter filling the space between the tile and plate and the perforations, but being substantially kept away from the foundation sheet 110

by said plates for preventing weakening the sheet by the wet cement.

2. The combination with a wall board foundation, of perforated filler plates secured to said foundation in spaced relation, sheet metal tiles disposed over said plates, there being a filler plate within each tile, and means bonding said tiles to said plates.

3. The combination with a foundation sheet, 10 of spaced perforated filler plates of fibrous insulating material secured to said sheet, rearwardly

flanged tiles disposed over said plates, and cement bonding said tiles to said plates.

4. A wall comprising a foundation sheet, spaced filler plates secured to said sheet, shell-like tiles disposed over said plates, and means bonding said tiles to said plates, the latter filling the space between the tile and plate but being substantially kept away from the foundation sheet by said plates, said plates having recesses for receiving said bonding means.
